S. A. WALKER,
CAR SEAT BACK.
APPLICATION FILED JULY 9, 1918.

Patented Apr. 15, 1919.

Inventor
Sheridan A. Walker

—By Wm. Bond
Attnm.

UNITED STATES PATENT OFFICE.

SHERIDAN A. WALKER, OF NEW YORK, N. Y., ASSIGNOR, BY MESNE ASSIGNMENTS, TO THE CARSON COMPANY, OF CHICAGO, ILLINOIS, A CORPORATION OF ILLINOIS.

CAR-SEAT BACK.

1,301,021.

Specification of Letters Patent. Patented Apr. 15, 1919.

Application filed July 9, 1918. Serial No. 244,068.

To all whom it may concern:

Be it known that I, SHERIDAN A. WALKER, a citizen of the United States, residing at New York, in the county of New York 5 and State of New York, have invented certain new and useful Improvements in Car-Seat Backs, of which the following is a specification.

The present invention relates to a means 10 by which covering material is attached to the body of a car seat back.

One object of the invention is to so attach the covering to the seat back body as to provide a narrow elongated slit, which will 15 serve to receive and retain a ticket.

A further object of the invention is to form the walls of said slit from the covering material, whereby the material itself will exert a frictional hold upon the ticket, 20 tending to prevent accidental displacement thereof from the slit.

A further object of the invention is to provide a slot or recess in the frame of the back, into which the ragged edges of adjacent 25 ends of the covering material will be placed and secured, and when so secured there will be a slit produced by the secured ends, which will constitute a receptacle for the purpose of receiving a ticket.

30 A further object of the invention is to neatly and securely attach the said covering to the seat body in a manner to eliminate the use of tapes, molding, or binders, heretofore employed for the purpose of concealing the ragged edges of the covering material.

40 A further object of the invention is to apply the covering to the seat back in such manner as to cause it to assume and retain a neat and finished appearance, and eliminate the constant repair which is necessitated by the loosening of the now-employed tape or binding.

The invention further consists in the features of construction and combination of parts hereinafter described and claimed.

In the drawings:

Figure 1 is a perspective of a car seat back made in accordance with the present 50 invention; and

Fig. 2 is a cross section showing a portion of the back and the manner in which the covering material is attached thereto and held in place.

55 In the art to which the present invention

relates, it has been the common practice to apply, along the top and side edges of a car seat back, a tape, molding, or similar covering strip, for the purpose of covering up or concealing the rough edges of the covering material. In use, these covering strips, particularly upon the top edge of the seat back, are employed for the purpose of retaining the check identifying the ticket which has been taken up from the passenger. 60 The forcing up of these covering strips for the purpose of inserting this identification check beneath the strip loosens them from proper securing in a relatively quick time, so that they become unsightly in appearance; 65 and, owing to the fact that they are in a direct line of vision to the passengers of the car, such unsightly appearance is highly undesirable, and the railroad companies are placed to a comparatively large amount of 70 expense and trouble in constantly repairing these loosened binding or covering strips.

The present invention deals with a method of securing the seat covering in place so that an efficient and firm connection is established 80 between the covering and the body of the seat back, which connection will be very difficult of disorganization, so that the seat will maintain a neat and finished appearance for a relatively long period of time. 85

Referring now to the drawings, the invention is illustrated in connection with a seat back 3, which may be of any suitable style and construction. The back comprises a body designated by the general number 4, 90 which may be of any suitable character. The body is represented in the drawing as comprising the springs, stuffing, supporting frame, etc., for the back. It is understood that the present invention is not to be limited in any particular by the construction of body herein shown, since the invention is capable of being employed with other and varied styles thereof.

The body has secured thereto a covering 100 5, of plush or other suitable material. The covering as shown comprises a section 6 and a section 7. The edges of the section 6 are designated by the numeral 8, and those of the section 7 by the numeral 9. In the construction shown, a portion of the frame of the body of the back comprises a rim 10 of wood or other suitable material, which is formed with a slot or recess 11. This rim 105 extends, as shown, along the upper and side 110

edges of the back, and the recess 11 continues around such edges, but in the construction shown in the drawings terminates along the side edges of the back at a point 5 indicated by the numeral 12 in Fig. 1, at which point it merges into an enlarged recess 13, which receives certain attaching portions from the rocker or other portion of the seat, although the length of the recess 10 11 may be varied as desired.

In applying the covering to the back, the outer edges of the covering sections are inserted into the slit 11 for the length which said slit extends, and for the remainder of 15 the distance the covering is tacked or otherwise secured in the usual manner; and since for such remaining distance, which is that embraced by the recess 13 and by the bottom edge of the back, the edges of the covering 20 are hidden from view, no tape or similar member is required to cover the ragged edges. Thus, by securing the covering in the manner of the present invention, the requirement for the use of tape, etc., is entirely 25 dispensed with.

By referring to Fig. 2, it will be seen that in carrying out the invention the end 8 of the covering section 6 is turned downward into the recess 11 and the end 9 of the covering section 7 is similarly turned down. By suitable means—glue or otherwise—these turned down ends are secured within said recess, with the pile 14 of the material, in such cases as where plush or similar material is employed, turned toward one another.

The two turned down ends when so secured are concealed and coöperate to form a narrow elongated slit 15, which extends from end to end of the top edge 16 of the 40 seat, and, as shown, partially down the side edges 17 thereof. Thus, the edges of the material are securely joined to the body of the back with the ragged edges of the material tucked in and concealed from view, 45 whereby nothing but the narrow elongated slit is visible, which gives a finished and smooth appearance to the back.

The slit formed by the covering material serves as a pocket or retainer for the reception 50 of the identifying check issued by the conductor. The slit is of such size as to readily permit the insertion of the check therein as shown in Fig. 1, and is sufficiently deep so as to hold it securely. The pile of 55 the fabric, when plush or similar material is used, acts as a friction means for retaining the check in position. As the check is forced downward in the slot, it will tend to force the pile away from the ticket and allow 60 the easy insertion of the latter. When, however, the ticket is removed, such movement will be resisted by the pile, which will then be moved toward the ticket and drag on the surface thereof, and, although this 65 resistance is not sufficient to interrupt or

impede the easy or quick removal of the check, it is sufficient to hold the check against accidental displacement.

By means of the foregoing, there is provided a connection between the seat back 70 body and its covering which is firm and efficient, which presents a neat and attractive appearance, which eliminates the use of binders, tapes, moldings, etc., that were a source of much annoyance by reason of their 75 constantly becoming loose, and which provides an efficient holding means for the identifying check and permits of the insertion and removal of such check without in any way weakening the securance of the covering 80 in position, so that the identifying check may be stuck in the seat back without any undesirable effects therefrom.

While the invention has been described with considerable particularity, it is understood to be limited only as may be by the terms of the appended claims.

I claim:

1. In a car seat back, the combination of a body, covering material for said body, 90 means for securing said covering to said back to provide an elongated slit-like aperture having the walls thereof formed of said covering material, and said aperture extending along the top edge of said back 95 and serving as a receptacle for tickets, substantially as described.

2. In a car seat back, the combination of a body, covering material for said body, means for securing said covering along a 100 portion of the outer edge of said body to provide an elongated slit-like aperture having the walls thereof formed of said covering material, and said aperture serving as a receptacle for tickets, substantially as de- 105 scribed.

3. In a car seat back, the combination of a body, covering material for said body, said body embodying a frame having a recess formed therein and extending along 110 the top edge thereof, means for securing the top edges of said covering material within said slot, whereby an elongated slit-like aperture is formed in the top edge of said back with the walls thereof consisting of 115 said covering material and said aperture serving as a receptacle for tickets, substantially as described.

4. In a car seat back, the combination of a body, covering material for said body, said 120 body embodying a frame formed with a recess extending along its top and side edges, said recess serving to receive and retain the edges of the covering material, whereby an elongated slit-like aperture is provided for 125 the distance of said recess having the walls thereof formed of said covering material, and said aperture constituting a receptacle for tickets, substantially as described.

5. In a car seat back, the combination of 130

a body, a covering of pile fabric for said body, means for securing the edges of said fabric to said back in a turned down relation, whereby an elongated slit-like aperture 5 is produced having the walls thereof formed of the adjacent surfaces of said pile fabric, said aperture extending along the top edge of the back and forming a receptacle for tickets, and said pile constituting a friction means for retaining the ticket in position within the aperture, substantially as described.

10 6. In a car seat back, the combination of

a body comprising a frame having a recess therein extending across the upper edge 15 thereof, covering material for said body, the edges of said material being inserted into said recess with the outside surfaces thereof secured to the walls of the recess and the inside surfaces coöperating to produce an 20 elongated slit-like aperture having the walls thereof formed of said covering material and constituting a receptacle for tickets, substantially as described.

SHERIDAN A. WALKER.
